CLAIM

The ornamental design for an armchair as shown and described.

DESCRIPTION

FIG. 1 is a top, front, right side perspective view of an armchair according to the present disclosure;

FIG. 2 is a bottom, front, left side perspective view of the armchair shown in FIG. 1;

FIG. 3 is a front view of the armchair shown in FIG. 1;

FIG. 4 is a rear view of the armchair shown in FIG. 1;

FIG. 5 is a left side view of the armchair shown in FIG. 1;

FIG. 6 is a left side view of the armchair shown in FIG. 1, shown in an alternative configuration;

FIG. 7 is a right side view of the armchair shown in FIG. 1;

FIG. 8 is a right side view of the armchair shown in FIG. 1, shown in an alternative configuration;

FIG. 9 is a top view of the armchair shown in FIG. 1; and,

FIG. 10 is a bottom view of the armchair shown in FIG. 1.

The broken lines in the drawings represent portions of the article that form no part of the claimed design.

1 Claim, 10 Drawing Sheets
